COMBINATION AUTOMOBILE HOOD ORNAMENT AND DISPLAY SIGN

John W. Knight, Byesville, Ohio

Application December 9, 1948, Serial No. 150,055

Term of patent 3½ years

(Cl. D48—32)

To all whom it may concern:

Be it known that I, John W. Knight, a citizen of the United States, residing at Byesville, in the county of Guernsey and State of Ohio, have invented a new, original, and ornamental Design for a Combination Automobile Hood Ornament and Display Sign, of which the following is a specification, reference being had to the accompanying drawing, forming a part thereof.

Fig. 1 is a perspective view of a combination automobile hood ornament and display sign showing my new design;

Fig. 2 is a top plan view thereof;

Fig. 3 is a front end elevational view;

Fig. 4 is a rear end elevational view.

The words "State Patrol" appearing in dotted lines on the present combination automobile hood ornament and display sign are for illustrative purposes only.

I claim:

The ornamental design for a combination automobile hood ornament and display sign, substantially as shown and described.

JOHN W. KNIGHT.
